UNITED STATES PATENT OFFICE.

HENRY J. SCHROEDER, OF SPRINGFIELD, ILLINOIS.

RAILWAY-CROSSING SIGNAL.

1,320,499.

Specification of Letters Patent.

Patented Nov. 4, 1919.

Application filed April 1, 1916. Serial No. 88,212.

To all whom it may concern:

Be it known that I, HENRY J. SCHROEDER, a citizen of the United States, residing at Springfield, in the county of Sangamon and 5 State of Illinois, have invented certain new and useful Improvements in Railway-Crossing Signals, of which the following is a specification.

This invention relates to improvements in 10 railway crossing signals of that class adapted to be operated by an on-coming train running over a portion of track included in an electric circuit and thereby closing the circuit. One object of the invention is to 15 provide a railway crossing signal including visual and audible elements located at or adjacent to a railway crossing whereby pedestrians and others at or near the crossing may be warned in the event of a train 20 approaching the crossing. With the foregoing and other objects in view the invention consists in the combination and arrangement of parts to be hereinafter fully described in this specification, pointed out 25 in the appended claim and illustrated in the accompanying drawings which form a part of the specification and in which—

Figure 1 is a front view of my signaling apparatus located beside a railroad track.

30 Fig. 2 is an enlarged sectional fragmentary view.

Fig. 3 is a longitudinal sectional view, enlarged, through one of the visual elements.

Fig. 4 is a diagrammatic view of the wiring for the signaling apparatus.

Like reference characters denote corresponding parts throughout the several views.

The reference numerals 1, 2 designate the 40 right and left tracks of a double track railway. My apparatus is located in the housing 3 arranged beside the railway adjacent a railway crossing. The housing 3 comprises a tower 4 through which the belting 45 5 runs that passes over a pulley 6 arranged upon transmission shaft 7 suitably supported in the housing 3, said shaft also carrying the gear wheel 8 that meshes with pinion 9 of the motor shaft 10 driven directly 50 by the motor 11 also arranged within the said housing. The said belt 5 passes from the pulley 6 over a sheave 12 arranged in the upper end of the tower 4 upon a sleeve 13 journaled in suitable bearings in said 55 tower and provided with the core 14 that revolves with said sleeve and carries with it

the T-coupling 15 that carries the arms 16, 17 in the remote or free ends of which the visual signaling elements 18 are carried. Within the said T-coupling 15 are the studs 60 19, 20 which extend through the core 14 and are connected respectively to the slip rings 21, 22 which in turn are connected, respectively by the brushes 23, 24 with the wires 25, 26 which extend, respectively, to 65 the trunk line 27 and to the common return 28 which extends from the railroad tracks 1, 2 to the motor 11.

Referring again to the visual signals, the same are provided with breathing caps 29 70 and said signals or lights are fed by the wires 30 that extend through arm 16, and wires 31 which extend through arm 17. To the tower 4 an insulated block with rubbing contacts 32 is secured and adapted for intermittent engagement with the swinging arms 16, 17 through spring contacts 50 more clearly shown at Fig. 1 whereby an electric circuit, which includes the bells 33, is closed. The said block is connected by feed 80 wire 34 with the trunk line, while a wire 35 connects the swinging arms 16, 17, with the bells 33 which are connected by wire 36 with the common return 28. The motor 11 is connected by wire 37 with the trunk line while 85 a wire 38 connects the trunk line and the railroad tracks.

Each railroad track is marked off into blocks bound by suitable insulation 39 and the operation of the signal is effected by a 90 railway train entering these blocks on either track. The blocks are located at approximately one thousand feet from each side of a railway crossing and the signal is placed adjacent the railway crossing. When a 95 train enters a block the steel wheels and trucks serve as circuit closers and connect the lines 38, 28 thus starting the motor and with it the commutator thus rotating the arms 16, 17 and lighting the visual signals 100 which remain lighted as long as the train is in the energized block. As the arms pass the block 32 they close the circuit in which the bells are located and so start the audible signals which are thus caused to ring intermittently and so attract the attention of all 105 pedestrians and others in the vicinity of the crossing and warn them of the danger of an approaching train.

Referring again to the sleeve 13 the same is 110 partly inclosed by a metal casing 40, which is formed with a vent 41, which serves as a

wet weather protector to keep moisture from the sleeve and core and serves to drain off any water that might seep into the revolving parts or travel along the sleeve.

5. What is claimed is:—

- A railway signaling device including a casing, with a sheave arranged therein, signaling arms provided with electrical lights, a sleeve journaled in said casing and having
10 an insulating core therein, said arms having a sleeve-connection with the aforesaid sleeve, studs extending through said core and wired to said electrical lights, and connected to slip-rings, said slip-rings being
15 connected with brushes, wires connected to said brushes, said wires extending to the trunk-line and to a common electrical re-

turn-member, respectively, extending from rails of the railway-tracks, a motor, means for transmitting motion from said motor to 20 said signaling arms, said casing having attached thereto a rubbing contact, and said signaling arms having resilient contacts, said rubbing contact and said resilient contacts being arranged for interengagement. 25

In testimony that I claim the foregoing as my own I have hereto affixed my signature in the presence of two subscribing witnesses.

HENRY J. SCHROEDER.
